SOFT HAMMERING HEAD

Myron Budd Mittleman, Larchmont, N. Y.

Application May 5, 1952, Serial No. 286,193

7 Claims. (Cl. 145—36)

The present invention relates to soft hammering heads adaptable for use in hammers, drifts and the like and more particularly to improvements in such heads of the type having a hollow portion or chamber therein.

As distinguished from hard hammers, soft hammers are softer than the work on which they are employed. They are commonly used to form soft metals, drive or knock apart close-fitting parts and, in general, wherever it is desired to strike a work piece without leaving a mark or changing its dimensions significantly. Materials sometimes employed for soft hammering heads include wood, rubber, rawhide, plastic, lead and copper alloys. Sometimes they are referred to as safety hammers, a description which stems from their non-ferrous content and hence their "safety" in explosive atmospheres where steel hammers might strike a spark.

Non-metallic heads generally require fairly large bulk for a given weight and, depending upon the material and work are subject to splintering, ripping, shredding, fracturing and mushrooming. Usually they have relatively short lives even for soft hammering heads which, as a class, are considered expendable tools. On the other hand, metallic heads, while of relatively longer usefulness are particularly subject to mushrooming about the striking face. Continued use after mushrooming causes a chipping of the upturned edges and hence a high rate of industrial accident.

In an attempt to minimize the peripheral upsetting of such striking faces, Gallant (U. S. Patent No. 2,355,641) described the use of an interior chamber or hollowed portion within the hammering head, but he specified that the front wall thickness between the chamber and striking surface should be thicker than the side walls and failed to make adequate provision to control the plastic flow of the metal comprising the head, with the result that heads made in accordance with Gallant's descriptions are still quite substantially subject to mushrooming and, relative to heads made in accordance with the present invention are unnecessarily short-lived.

An object of the present invention is to provide a soft hammering head constructed to minimize the likelihood of mushrooming about the striking surface.

A further object is the provision of such a head of longer usefulness than previously known soft hammers.

These and other objects are achieved, in a preferred form, by a hammering head of a soft material (such as copper or copper alloyed with a small amount of tin or zinc, depending upon the hardness required) which tapers generally from the eye or portions removed from the eye towards the striking surface, having a hollow chamber within the head, the front wall of said head, lying between the forward boundary of said chamber and the striking surface being of less thickness than the side walls bounding said chamber. A pair of opposite side walls may have undulating interior surfaces, preferably of serriform section. As an additional element to control the plastic flow of the metal, the junction of the unrounded interior side walls and the interior of the front or striking wall may be an oblique wedge shaped section.

Other objects and a fuller understanding of the present invention may be had by referring to the following description and claims, taken in conjunction with the accompanying drawing which illustrates preferred embodiments thereof, it being understood that the foregoing statement of objects of the invention and the brief summary thereof are intended to generally explain the same without limiting it in any manner.

2

Fig. 1 is a side elevation of a head for a soft hammer embodying the present invention, the handle therefore being shown in dashed outline.

Fig. 2 is a sectional view of the said elevation taken midway through the head.

Fig. 3 is the same sectional view as Fig. 2 but taken after the head has been pounded and at a point where it approaches the end of its use.

Fig. 4 is a section in elevation of the hammer of Fig. 1 but taken along line 4 of Fig. 2.

Fig. 5 is a similar section but taken along line 5 in Fig. 4 (of the pounded hammer).

Fig. 6 is a horizontal section of the hammer shown in Fig. 1 but taken along line 6—6 of Fig. 4.

Fig. 7 is an elevational view of a drift employing a hammering head embodying the present invention, portions thereof being cut away to reveal the inner construction.

Referring to the drawing, and more particularly to the embodiment of the invention as shown in Figs. 1 through 6, it comprises a soft hammering head preferably of a copper alloy which generally tapers towards the end or striking surfaces 10 and 11 having substantially normal surface center panels 12, 13, 14 and 15, and tapering surface end panels 16, 17, 18 and 19 in the lower half of the head (as shown in the drawings) and 20, 21, 22, 23 in the upper half of said head, the junctions of the center panels, the junctions of the side panels and the junctions of the terminal portions of the side panels with the striking faces being bevelled. An eye 24, adapted to receive a hammer handle 25 extends transversely through center panels 13 and 16, said handle being secured to said head by a pin 26 placed in the bore 27 extending through panels 12 and 14 as well as handle 25. The junction of panel 15 with the upper and lower surfaces of eye 24 are bevelled to form oblique surfaces 28 and 29.

Internally, the head contains lower and upper chambers 30 and 31, in communication with eye 24 (to permit easy casting), said chambers being roughly oblong in vertical sections parallel to the center panels, the interior of the opposed side walls 32 and 33 of lower chamber 30, being the walls extending from said chamber to panels 12 and 16 on one side and 14 and 18 in the other respectively, having substantially planar interior surfaces substantially parallel with center panels 12 and 14 respectively, while the remaining opposed side walls 34 and 35 of lower chamber 30 are undulating, having indented portions 34a, 34b, and 34c and 35a, 35b and 35c respectively leaving inwardly extending ridges 34d and 34e and 35d and 35e, respectively, forming walls of serriform outline. At the junction of side walls 32 and 33 and front (or striking) wall 36 of chamber 30 are oblique surfaces 37 and 38 substantially parallel to the faces of the bevels at the junctions of end panels 16 and 18 with striking surface 10. The undulations or serrations are formed in said side walls to lend structural strength to the walls and at the same time assist in the control of the plastic flow of the metal of the head under conditions of use.

Since chamber 31 is constructed identically with chamber 30, primes are employed to designate the corresponding elements.

The head is made by a conventional casting process. Handle 25 is then inserted in eye 24, and pin 26 is passed through bores 27 in the head and handle to complete the assembly.

After the hammer has been used, the changes observable in Figs. 3 and 5 take place. Generally, the hammer becomes shorter longitudinally and broader transversely. Similarly chambers 30 and 31 become shorter longitudinally and broader transversely. There is no falling in of the metal laterally upon the undulating side walls, but on the contrary an outward flow. Since when both striking surfaces of the hammer are used each half transforms symmetrically, it will suffice to note the changes in the lower half.

Front or striking wall 36 becomes somewhat thicker longitudinally and substantially wider laterally. Oblique surfaces 37 and 38 disappear, striking wall 36 having pushed up upon them. Side walls 34 and 35 become thicker, more so near striking wall 36 than near eye 24.

The distance between indentations 34a and 35a in side walls 34 and 35 increase substantially and the interior surfaces of the portions of said walls between said indentations and the interior surface of the striking wall bow inwards. The corresponding lateral distances between ridges 34d and 35d, between indentations 34b and 35b, between ridges 34e and 35e and between indentations 34c and 35c likewise increase, but the extent of such widening decreases as eye 24 is approached. End panels 17 and 19 depart slightly from their original linear surface and appear somewhat convex longitudinally.

The plastic flow of the metal is such that eye 24 narrows and compresses handle 25, binding it tighter with use. Oblique surfaces 28 and 29 are effective to prevent the longitudinally-inwardly pressed metal about the lateral periphery of the eye at said surfaces from biting into the wooden handle, and causing the same to be snapped off. On the other lateral periphery of said eye, at panel 13, the outward travel of the metal is such as to cause a slight but noticeable bow, giving panel 13, which was originally planar, a concave surface.

Side walls 32 and 33 (those with the inner planar surfaces) thicken, more greatly near striking wall 36 and less so proximate bore 27. Striking surface 10, when laterally viewed as in Fig. 5, appears convex, the metal about the edges having travelled further toward bore 27 than that in the middle portion. The inner surface of striking wall 36 is correspondingly changed in shape and appears concave. It is believed that the buttressing effect of the wedge shaped junctions of side walls 16 and 18 with the inner surface of striking wall 36, presenting oblique surfaces 37 and 38 causes this resulting convexity of the striking surface by angularly channelling metal flow outwardly and upwardly.

The thickening or outward movement of side walls 32 and 33 causes pin 26 to appear countersunk in panels 12 and 14.

Significantly, there is no mushrooming at the striking surface and the head retains generally its tapered outline throughout its useful life. By reason of the improved means of channelling the plastic flow of the metal, while it of course is subject to a forging effect, i. e., a hardening at the striking surface with use, it is superior to known hammers in that it takes a great deal of use to harden it to the point of hardness which other hammers reach with much less use.

It is critical to the success of the hammer described that striking wall 36 be narrower than the side walls. To understand why, it is necessary to analyze what happens upon impact with a work piece and shortly thereafter.

Take first, the case of a solid copper-alloy hammer. Assume it is composed of discrete particles which are held together by cohesive forces but which particles are nevertheless loosely packed so that the hammer may be compressed. The hammer is swung so that it will hit a planar work piece normally thereto. As the hammer is moved, each constituent particle is given a certain momentum and at the instant preceding impact all are travelling at the same velocity. At the moment of impact, each particle tends, in accordance with Newton's first law of motion, to continue in a straight line, e. g. normal to the work surface. Ignoring for the moment the cohesive forces at work in the hammer head and the shapes of the particles, each particle is driven forward into contact with its forward neighbor, except the terminal particles in the striking surface which strike the harder surface of the work piece and may be deemed relatively to stand still. The distance each particle travels will then be a function of its distance from the striking surface and the elasticity of the particles. The force exerted upon the terminal particles would be a function of the momentum of the individual particles lying rearward of the striking surface.

However, the particles are not sheets, having irregular surfaces and therefore upon collision with forward neighbors some would be deflected. Hence there are lateral components of movement and force upon the collisions. Manifestly, these are much smaller than the longitudinal movements and forces. Hence while most of the metal moves downward on impact some of it is caused to move laterally. If a lateral slice across the hammer head is considered, then the more mass in such slice, the greater the lateral component. When the

hammer is solid, assuming initially upon impact the lateral forces are equally distributed, since it is "easier" for the particles to move outward toward the lateral surfaces of the slice than inwardly to compact the slice, more metal will move laterally outwardly than laterally inwardly. It may be concluded then, that the more mass there is in a horizontal slice of the hammer, the more the slice will "grow" laterally on impact. Of course, after impact, the elasticity of the hammer head operates to tend to restore it to its original shape, but it does not quite do so, there being some residual displacement (plastic flow). Since the greatest force is exerted upon the terminal layer, that is where mushrooming takes place.

10 In accordance with the above, it is then wise to have a chambered hammer head since then the number of particles which may flow against the striking surface directly, upon impact is minimized. Of course, the cohesive forces at work in the head cause the greater portion of the momentum of the particles to be transmitted to the striking surface, but they are then applied in such a way that lateral particle flow in the terminal layer is minimized. But doubly important is the correlative conclusion that the thinner the striking wall the less the laterally outward travel at this most critical area, and hence the minimization of the tendency to mushroom.

20 Confirmation of the validity of the "lateral slice" analysis is found in the fact that walls 34 and 35 do not 30 collapse toward each other upon use of the hammer, but actually move apart. Each of said walls are connected at both ends to solid walls 32 and 33 which act as would the solid hammer first posited. The expansion of these 35 solid walls in accordance with the principles outlined above causes them to carry the serrated walls away from each other.

25 To give strength to walls 34 and 35 they were given the serriform section shown. To maintain the dimensional or structural stability of the hammer it is necessary that the side walls be thicker than the striking surface, the thickness of which has been kept to a minimum in accordance with the principles developed above.

Another confirmation of the "lateral slice" approach 30 may be observed in the flow about handle 25, there being the lessening of lateral flow immediately proximate the handle due to the fact that flow is easier against the soft wood handle than against metal causing the concavity in panel 13. Similarly, the other displacements upon use may be similarly employed to support the 40 analysis. Then, too, when only one side of the head is pounded, metal flows from the unpounded portion adjoining eye 24 into the eye and against the wood of handle 25 and also slightly laterally to similarly form the type of concavity mentioned above.

45 Another embodiment of the present invention is shown in Fig. 7 which illustrates a drift incorporating a hammering head 39 similar in all respects to the one previously described except that it has less serrations and the handle, in this instance preferably brass handle 40, 50 is longitudinally axially associated with the head being secured thereto by a pin 41 passing through aligned bores 42 in said head and handle. A washer 43 acts to seat handle 40 on head 39. For better gripping a rubber sleeve 44 is placed about said handle and held in 55 place by an upper washer 45 riveted to the top of handle 40. Said upper washer also acts as a detent for the user's hand.

55 Although the subject invention has been described with a certain degree of particularity, it is understood that the present disclosure has been made only by way of example and that numerous additional changes in the details of construction, combination and arrangement may be resorted to without transcending the scope of 70 the invention as hereinafter claimed.

What is claimed is:

1. A soft hammering head formed of a relatively soft plastically deformable material, including a body, having a chamber formed therein, said chamber being 80 defined by side walls and a front striking wall, the thickness of said side walls proximate the junction with said front striking wall being greater than the thickness of said front striking wall, lower portions of said side walls tapering toward said striking wall.

85 2. A soft hammering head as described in claim 1, a

pair of opposing side walls having inner undulating surfaces.

3. A soft hammering head as described in claim 2, said undulating surfaces being serriform in section.

4. A soft hammering head as described in claim 3, the portions of said side walls of serriform section proximate the junctions with said striking wall sloping initially outwardly from said striking wall.

5. A soft hammering head as described in claim 1, a pair of opposing walls having substantially planar surfaces, such side walls and said striking wall meeting at a solid oblique corner.

6. A soft hammer head having a body of greater longitudinal than lateral extent and having a centrally laterally extending eye therethrough adapted to receive a handle, and having two chambers formed therein one on either side of said eye, each of said chambers being defined by side walls and terminal striking walls, the thickness of said side walls proximate the junction with said front striking wall being greater than the thickness of said striking walls, exterior portions of said side walls proximate said striking wall tapering toward said striking walls,

a pair of opposing side walls in each such chamber having inner undulating surfaces.

7. A soft hammering head for a drift formed of a relatively soft plastically deformable material having an axial cavity formed therein, the upper portion of the said cavity comprising an eye adapted to receive a handle and the lower portion thereof being laterally defined by side walls and terminally defined by a front striking wall, said striking wall being thinner than the thickness of said side walls proximate the junction with said front striking wall, said side walls having inner undulating surfaces, exterior portions of said side walls proximate said striking wall tapering inwardly toward said striking wall.
